Application February 15, 1954, Serial No. 410,215

15 Claims. (Cl. 5—63)

This invention relates in general to sick-room furniture and more particularly hospital beds.

Conventional invalid beds and hospital beds are constructed in such a manner that the spring and mattress are located at a relatively high fixed level above the floor so as to be convenient for the nurses, doctors and attendants in administering to the patient. Recent consideration of sick-room procedures, however, has indicated that a patient will recover or convalesce more rapidly and more comfortably if the physical surroundings in the hospital room are less forbidding and resemble as nearly as possible the appearance of a normal dwelling room. It has been found that the type of bed used is one of the most significant psychological aspects of the problem since practically all patients are accustomed to sleeping in beds of conventional height above the floor and are subconsciously disturbed by the necessity of sleeping at a greatly increased height when confined to a hospital bed of the conventional type. Closely related to the psychological aspects of the problem is the further matter of patient convenience during the ambulatory stages of convalescence. Once a patient is sufficiently recovered to care for many of his personal needs such as going to the bathroom for washing, bathing, and other functions, the difficulties and hazards encountered in getting out of and back into a high bed are substantial and serious. However, it is desirable not only to provide a bed which can be varied in height but also one which can be shifted up and down by power driven means.

It is, therefore, the primary object of the present invention to provide a power-driven hospital bed which can be adjusted to various horizontal levels so that the patient can sleep or recline at any desired height above the floor within selected limits.

It is also an object of the present invention to provide a power-driven hospital bed of the type stated which when in its lowermost position of adjustment will closely simulate a conventional domestic bed.

It is a further object of the present invention to provide a power-driven hospital bed which can be controlled by the patient or the attendant easily, conveniently and with a minimum of physical effort and which during movement from one position to another will operate smoothly without jarring the patient.

With the above and other objects in view, our invention resides in the novel features of form, construction, arrangement, and combination of parts presently described and pointed out in the claims.

In the accompanying drawings—

Figure 1 is a perspective view of a variable-height hospital bed, the bed ends and associated operative elements being shown in full lines and the bed spring supported thereby being shown in dotted lines;

Figure 2 is a side elevational view of the hospital bed embodying the present invention;

Figure 3 is an end elevational view of the hospital bed embodying the present invention;

2

Figure 4 is a fragmentary sectional view taken approximately along line 4—4 of Figure 3;

Figures 5 and 6 are fragmentary sectional views taken approximately along lines 5—5 and 6—6 of Figure 2;

Figure 7 is a fragmentary top plan view of the hospital bed embodying the present invention;

Figures 8 and 9 are fragmentary sectional views taken approximately along lines 8—8 and 9—9 of Figure 3;

Figure 10 is a fragmentary sectional view taken approximately along line 10—10 of Figure 8;

Figure 11 is a fragmentary sectional view taken approximately along line 11—11 of Figure 2;

Figure 12 is a fragmentary sectional view taken approximately along line 12—12 of Figure 8;

Figure 13 is a fragmentary sectional view taken approximately along line 13—13 of Figure 7; and

Figure 14 is a diagrammatic view illustrating the cable and pulley system forming a part of the present invention.

Referring now in more detail and by reference characters to the drawings which illustrate a practical embodiment of the present invention, A designates a hospital bed comprising a head-board 1 and a foot-board 2 structurally interconnected in bed-forming relationship by a frame 3 including side rails 4, 5, cross-connected by end rails 6, 7, and being adapted to support a conventional articulated bed-spring 8 shown in dotted lines in Figure 2, and having actuator cranks 9, 10, by which it can be moved into various relatively inclined positions for the comfort of the patient. The bed spring 8 is conventional and, therefore, is not described or illustrated in extensive detail. The side rails 4, 5, are respectively provided with hook-plates 11, 12, and 11', 12', for conventional engagement with complementary fittings 13, 13', 14, 14', of the head-board 1 and foot-board 2 whereby the bed A is held in upright or operative position as shown in Figures 1 and 2. It should be understood, of course, that other types of conventional bed-rail hardware can be employed equally well.

The head-board 1 comprises a pair of tubular open-bottomed stiles 15, 15', cross-connected by a hollow top rail 16 and a hollow bottom rail 17, all of rectangular cross-sectional shape and forming a frame for a relatively thin panel 18 which may be of any desired decorative surface appearance. The under side of the bottom rail 17 is provided with an elongated slot s the rear margin of which is defined by a horizontal flange 17'. Operatively disposed in snug-fitting slidable relation within the stiles 15, 15', are tubular leg members 19, 19', respectively, each integrally including four walls 20, 21, 22, 23, and 20', 21', 22', and 23'. The leg members 19, 19', are respectively provided adjacent their lower ends with rigidly welded caster-sockets 24, 24', for operatively receiving swiveling casters 25, 25'. The leg members 19, 19' are also respectively provided at their upper ends with rigidly welded top-plates 26, 26', having centrally located apertures 27, 27'. Finally, the inwardly and forwardly presented faces 22, 23, 22', 23', of the leg members 19, 19', are respectively provided with elongated closed-ended slots 28, 29, 28', 29'. The forwardly presented faces 30, 30', of the stiles 15, 15', respectively, are provided with short slots 31, 31', which are aligned with the slots 29, 29', and welded to the faces 30, 30', in line with the slots 31, 31', thereof are short forwardly projecting tubular sleeves 32, 32', for operatively housing pulleys 33, 33', respectively, as best seen in Figure 8. Similarly, the inwardly presented faces 34, 34', of the stiles 15, 15', respectively, are provided with short slots 35, 35', which are aligned with the slots 29, 29', and welded to the faces 34, 34', in line with the slots 35, 35', are short inwardly projecting tubular sleeves 36, 36', for operatively housing pulleys 37, 37'.

The foot-board 2 is of substantially similar construction

to the head-board 1 and comprises a pair of tubular open bottom stiles 38, 38', cross-connected by a hollow top rail 39 and a hollow bottom rail 40, all of rectangular cross-sectional shape and forming a frame for a relatively thin panel 41 which is decorated to match the panel 18. It should be noted in this connection that the lower horizontal margin of the bottom rail 40 is located in upwardly spaced relationship to the fittings 14, 14', and the spring rail 7 so that the actuator cranks 9, 10, will project outwardly in convenient free-turning relation directly beneath the bottom of the foot-board 2, substantially as shown in Figure 1. Furthermore, the over-all height of the foot-board 2 is preferably shorter than the over-all height of the head-board 1 so that the two ends of the bed will assume visual appearance which is more or less conventional, that is to say, substantially similar to the proportions and dimensions of the head-board and foot-board of a domestic type of bed.

Operatively disposed in snug-fitting slidable relation within the stiles 38, 38', are tubular leg members 42, 42', respectively, each integrally including four walls 43, 44, 45, 46, and 43', 44', 45', and 46'. The leg members 42, 42', are respectively provided adjacent their lower ends with rigidly welded caster-sockets 47, 47', for operatively receiving swiveling casters 48, 48'. The leg members 42, 42' are also provided at their upper ends with rigidly welded top plates 49, 49', having centrally located apertures 50, 50'.

The rearwardly presented faces 46 and 46' of the leg members 42, 42', are respectively provided with elongated closed-ended slots 51, 51', and the rearwardly presented faces 52, 52', of the stiles 38, 38', respectively, are provided with short slots 53, 53', which are respectively aligned with the slots 51, 51'. Welded to the rearwardly presented faces 52, 52', in line with the slots 51, 51', are short rearwardly projecting tubular sleeves 54, 54', for operatively housing pulleys 55, 55', respectively, as best seen in Figures 7 and 8.

Welded rigidly within the leg members 19, 19', respectively, are horizontal catch plates 56, 56', located adjacent to but in upwardly spaced relation to the lower ends of the slots 29, 29'. The catch-plates 56, 56', are identical and are provided centrally of their forwardly presented edges with inwardly extending slots 57, 57', and their under faces with circular indentations 58, 58', located at the inner ends of the slots 57, 57', in the provision of sockets for retentively engaging the enlarged end of ball fittings 59, 59', which are securely and tightly fastened to the ends of strong braided steel wire cables 60, 60'.

Removably mounted by means of screws 61 to each of the bed-spring side rails 4, 5, adjacent the forward ends thereof, respectively, are pulley brackets 62 for rotatably supporting idler pulleys 63 which are rotatably journaled upon pulley spindles 64 and serve to support the cables 60, 60', in substantially horizontal and concealed position along the inside faces of the bed-spring rails 4, 5, as best seen in Figure 1.

Bolted or otherwise rigidly attached at its ends to the side rails 4, 5, and extending therebetween is a metal hanger-strap 65 having a centrally located flat horizontal portion 66 for supporting the forward end of a rectilinear shell or housing 67 formed preferably of heavy sheet metal and including a bottom wall 68, top wall 69, side walls 70, 71, front wall 72 and a rear wall 73. The rear portion of the side wall 70 is integrally provided with a laterally projecting rectilinear side-compartment 74 for housing a reversible electric motor 75 connected by conventional conductor-cords 76, 77 to a reversing switch 78 and to a source of electric power (not shown). The switching means and circuit, being substantially conventional, are not shown in detail. The motor 75 is mechanically connected through a shaft coupling 79 to the input shaft 80 of a gear-type speed reducer 81 which is

in turn rigidly bolted to the bottom wall 68 and is mechanically connected by a shaft coupling 82 to the rear end of a drive-screw 83, the latter being journaled at its forward end in a bearing 84 mounted on the inner face 5 of the front wall 72. Also mounted on the inner face of the front wall 72 in equidistantly spaced lateral relation to the drive-screw 83 are two horizontal slide-rods 85, 86, for shiftably supporting a relatively strong, rigidly-made draw-frame 87 having a centrally located nut 88 for threaded engagement with the drive-screw 83. At its outer ends the draw-frame 87 is slotted and socketed as at 89, 89', in a manner similar to the catch-plates 56, 56', for receiving the enlarged ends of ball fittings 90, 90', which are securely and tightly fastened to the ends of braided steel wire cables 91, 91', all as best seen in Figures 7 and 13.

The rear wall 73 of the housing 67 extends upwardly through the slot 5 of the head-board bottom-rail 17 and is bent over upon the flange 17' for securement thereto by bolts 92 and nuts 93 with interposed rubber washers 94 to deaden noise and vibration. Operatively mounted on the rear wall 73 in the upper rear corners of the housing 67 are appropriately slanted pulleys 95, 95'. It should be noted in this connection that the top wall 69 of the housing 67 does not extend all the way to the rear wall 73 thereby forming a slot-like opening 96 in the upper rear end of the housing 67 directly beneath the slot 5.

The cables 60, 60', and 91, 91' are operatively trained 30 over the various pulleys in the manner schematically shown in Figure 14 and are endwise securely fastened within externally threaded terminal sleeves 97, 97', 98, 98', which respectively project upwardly through the apertures 27, 27', 50, 50', and are provided with nuts 99, 99', 100, 100', by which the relative vertical positions of the terminal ends of the cables 60, 60', 91, 91', may be adjusted. In order to facilitate such vertical adjustment the sleeves 97, 97', 98, 98', are each integrally provided at its lower end with a diametrically enlarged hexagonal collar section 101 which is slidably fitted within a slide channel 102 welded upon and projecting downwardly from the under sides of each of the top plates 26, 26', 49, 49', substantially in the manner shown in Figures 5 and 8. Finally, each of the stiles 15, 15' and 38 are 40 provided in their top walls with identical apertures 103 which are provided with conventional snap-fitted closure plugs 104. The latter may be manually removed and an elongated socket wrench inserted through the apertures 103 to engage the nuts 99, 99', 100, 100', whereby the relative vertical position of the sleeves 97, 97', 98, 98', may be accordingly adjusted so that the several cables 60, 60', 91, 91', will all be equally taut and the relative vertical positions of the legs 19, 19', 42, 42', will be adjusted in relation to each other so that the head-board 1 and foot-board 2 will be substantially upright and the bed-spring 8 will be substantially horizontal when the entire structure is assembled for use.

Assuming that the variable height bed A when assembled for use is in its lowermost position, it may be very quickly and conveniently shifted upwardly by manipulating the switch 77 and energizing the motor 75. Thereupon, the drive-screw 83 will be rotated driving the draw-frame 87 relatively forward toward the foot-board 2 pulling with it the cables 91, 91', thus transmitting downward relative movement to the legs 19, 19', which in turn move relatively downward with respect to the head-board 1 pulling with them the cables 60, 60', which extend forwardly along the undersides of the rails 4, 5, and accordingly transmit downward relative movement to the leg members 42, 42'. Since the cables 60, 60', 91, 91', are all taut and have been adjusted as above described, the four legs 19, 19', 42, 42', will all move simultaneously. It will, of course, be understood in this connection that the 55 above-mentioned downward relative movement of the

leg members 19, 19', 42, 42', is actually translated into upward movement of the head-board 1, foot-board 2 and bed-spring 8 as a unit, since the casters 25, 25', 48, 48', rest upon the floor and the leg members 19, 19', 42, 42', are actually stationary.

The bed A can, of course, be shifted to its uppermost position, in which it is at a so-called "hospital height" for the convenience of the nurses or doctor in handling the patient, or if desired can be stopped at any intermediate position and can be returned to its lowermost position when the patient is merely resting or sleeping. Furthermore, the switch 78 can be located in a position at which it is in convenient reach of the patient who then can raise and lower the bed at will.

It should be understood that changes and modifications in the form, construction, arrangement, and combination of the several parts of the hospital bed may be made and substituted for those herein shown and described without departing from the nature and principle of our invention.

Having thus described our invention, what we claim and desire to secure by Letters Patent is:

1. A hospital bed including a headboard and a foot-board rigidly connected by spaced parallel side rails to define a rectangular bed-spring supporting structure provided at its four corners with downwardly opening, tubular leg-receiving elements, a leg shiftably mounted in each leg-receiving element, power-driven means carried by the bed-spring supporting structure, flexible cables connecting the upper ends of the headboard legs to the power driven means, and flexible cables connecting the lower ends of said headboard legs to the upper ends of the footboard legs for causing all four of the legs to move simultaneously.

2. A hospital bed including two spaced upright parallel end members rigidly interconnected by means of horizontal bed rails, each end member having tubular leg-receiving elements, a leg shiftably mounted in each leg-receiving element, a housing mounted on one of the end members and extending between the bed rails, a horizontal jack-screw rotatably mounted in the housing, a slide element shiftably mounted in the housing and being provided with a nut operatively engaged with said jack-screw, flexible cable means connecting one end of at least one leg in one end member to the slide element, flexible cable means connecting the other end of said last-mentioned leg member to one end of one leg in the other end member, and means for rotating the jack-screw whereby to cause the end members to move upwardly together.

3. A hospital bed including two spaced parallel upright end members rigidly interconnected by means of horizontal bed rails, each end member having tubular leg-receiving elements, a leg shiftably mounted in each leg-receiving element, a housing carried by one of the end members and extending between and below the bed rails, a horizontal jack-screw rotatably mounted in the housing, a slide element shiftably mounted in the housing and being provided with a nut operatively engaged with said jack-screw, flexible cable means connecting the upper end of at least one leg in one end member to the slide element, flexible cable means connecting the lower end of said last-mentioned leg member to the upper end of one leg in the other end member, and means for rotating the jack-screw whereby to cause the end members to move upwardly together.

4. A hospital bed including two spaced parallel upright end members rigidly interconnected by means of horizontal bed rails, each end member having a plurality of tubular leg-receiving elements, a leg shiftably mounted in each leg-receiving element, a housing carried by one of the end members and extending between the bed rails, a horizontal jack-screw rotatably mounted in the housing, a slide element shiftably mounted in the housing and being provided with a nut operatively engaged with

said jack-screw, flexible cable means connecting the upper ends of the legs in one member to the slide element, flexible cable means connecting the lower ends of the legs in said one end member to the upper ends of the legs in said other end member, and means for rotating the jack-screw whereby to cause the end members to move upwardly together.

5. A hospital bed including two spaced parallel upright end members rigidly interconnected by means of horizontal bed rails, each end member having a pair of tubular leg-receiving elements, a leg shiftably mounted in each leg-receiving element, a housing mounted on one of the end members and extending between the bed rails, a horizontal jack-screw rotatably mounted in the housing, a slide element shiftably mounted in the housing and being provided with a nut operatively engaged with said jack-screw, flexible cable means connecting the upper ends of the legs in one end member to the slide element, flexible cable means connecting the lower ends of the legs in said one end member to the upper ends of the legs in said other end member, and motor means for rotating the jack-screw whereby to cause the end members to move upwardly together.

6. A hospital bed including two spaced parallel end members rigidly interconnected by means of horizontal bed rails, each end member having a plurality of tubular leg-receiving elements, a leg shiftably mounted in each leg-receiving element, driving means carried by the bed, a pulley operatively carried by each leg-receiving element, two flexible cables trained around the pulleys, each cable being connected at its ends respectively to the upper end of one leg in one end member and the lower end of another leg in the other end member, thereby connecting each leg of one end member with a corresponding leg of the other end member lengthwise of the bed, auxiliary pulleys operatively carried by the leg-receiving elements of one of the end members, flexible cables connected to each of the legs mounted in said last-named leg-receiving elements and being respectively trained around the auxiliary pulleys, said last-mentioned flexible cables also being connected to the driving means for causing the end members to move simultaneously.

7. A hospital bed including a headboard and a foot-board rigidly connected by spaced parallel side rails to define a rectangular bed-spring supporting structure provided at its four corners with downwardly opening tubular leg-receiving elements, a leg shiftably mounted in each leg-receiving element, driving means carried by the bed-spring supporting structure, flexible cables connecting the upper ends of the headboard legs to the driving means, and flexible cables connecting the lower ends of said headboard legs to the upper ends of the footboard legs for causing all four of the legs to move simultaneously.

8. A hospital bed including a headboard and a foot-board rigidly connected by spaced parallel side rails to define a rectangular bed-spring supporting structure provided at its four corners with downwardly opening tubular leg-receiving elements, a leg shiftably mounted in each leg-receiving element, power-driven means carried by the bed-spring supporting structure, flexible cables connecting the upper ends of the headboard legs to the power-driven means, and flexible cables extending along said side rails and connecting the lower ends of said headboard legs to the upper ends of the footboard legs for causing all four of the legs to move simultaneously.

9. A hospital bed including a headboard and a foot-board rigidly connected by spaced parallel side rails to define a rectangular bed-spring supporting structure provided at its four corners with downwardly opening tubular leg-receiving elements, a leg shiftably mounted in each leg-receiving element, power-driven means carried by said bed-spring supporting structure, flexible cables connecting the upper ends of the headboard legs to the power-driven means, and flexible cables connecting the lower ends of each of the headboard legs to the upper end

of its corresponding footboard leg for causing all four of the legs to move simultaneously.

10. A hospital bed including two spaced upright parallel end members rigidly interconnected by means of horizontal bed rails, each end member having tubular leg-receiving elements, a leg shiftably mounted in each leg-receiving element, power-driven means carried by one of the end members, flexible cables connecting the upper ends of the legs in one end member to the power-driven means, and flexible cables connecting the lower ends of the legs in said one end member to the upper ends of the legs in said other end member for causing all the legs to move simultaneously.

11. A hospital bed including two spaced upright parallel end members rigidly interconnected by means of horizontal bed rails, each end member having tubular leg-receiving elements, a leg shiftably mounted in each leg-receiving element, power-driven means carried by one of the end members, flexible cables connecting the upper ends of the legs in one end member to the power-driven means, and flexible cables extending along said rails and connecting the lower ends of the legs in said one end member to the upper ends of the legs in said other end member for causing all the legs to move simultaneously.

12. A hospital bed including a headboard and a footboard rigidly connected by means of horizontal bed rails to define a bed-spring supporting structure, said headboard and footboard each having a pair of tubular leg-receiving elements, a leg shiftably mounted in each leg-receiving element, power-driven means carried by the bed-spring supporting structure, a pulley operatively carried by each leg-receiving element, and flexible cables trained around the pulleys, said cables connecting the upper ends of the headboard legs to power-driven means, said flexible cables also connecting the lower ends of the headboard legs to the upper ends of the footboard legs for causing all four legs to move simultaneously.

13. A hospital bed including a headboard and a footboard rigidly connected by spaced parallel side rails to define a rectangular bed-spring supporting structure provided at its four corners with downwardly opening tubu-

lar leg-receiving elements, a leg shiftably mounted in each leg-receiving element, power-driven means carried by the bed-spring supporting structure, flexible cables connecting the headboard legs to the power-driven means, and flexible cables connecting the headboard legs to the footboard legs for causing all four legs to move simultaneously.

14. A hospital bed including two spaced parallel end members rigidly interconnected by means of horizontal bed rails to define a bed-spring supporting structure provided at its four corners with downwardly opening tubular leg-receiving elements, a leg shiftably mounted in each leg-receiving element, power-driven means carried by the bed-spring supporting structure, flexible cables connecting the legs in one end member to the power-driven means, and flexible cables connecting said last-mentioned legs to the legs in the other end member for causing the end members to move simultaneously.

15. A hospital bed including two spaced parallel end members rigidly interconnected by means of horizontal bed rails to define a bed-spring supporting structure provided at its four corners with downwardly opening tubular leg-receiving elements, a leg shiftably mounted in each leg-receiving element, power-driven means carried by the bed-spring supporting structure, flexible cables connecting the upper ends of the legs in one end member to the power-driven means, and flexible cables connecting the lower ends of said last-mentioned legs to the upper ends of the legs in the other end member for causing the end members to move simultaneously.
